UNITED STATES PATENT OFFICE.

FREDERICK HENRY DE VEULLE, OF HANDSWORTH, ENGLAND, ASSIGNOR TO AMAC LIMITED, OF BIRMINGHAM, ENGLAND.

CARBURETOR FOR INTERNAL-COMBUSTION ENGINES.

Application filed August 2, 1921. Serial No. 489,223.

(GRANTED UNDER THE PROVISIONS OF THE ACT OF MARCH 3, 1921, 41 STAT. L., 1313.)

To all whom it may concern:

Be it known that I, FREDERICK HENRY DE VEULLE, a subject of the King of England, residing at Handsworth, Birmingham, England, have invented certain new and useful Improvements in Carburetors for Internal Combustion Engines (for which I have filed applications in Great Britain, April 30, 1914, Patent No. 10,649; in France, March 17, 1920, application No. 124,495, and in Germany, March 4, 1920, application No. 15,366), of which the following is a specification.

This invention relates to carburetors of the kind having a tubular valve with a jet outlet arranged at one end of the valve, the valve being movable either by sliding or rotating so as to control the admission of air to the jet outlet and the delivery of mixture from the spraying chamber or induction tube.

It is the object of the present invention to provide means whereby the surface opposite the fuel nozzle and within the walls of the valve conforms in the fully open position of the valve, with the shape of the rest of the induction tube. Usually the induction tube gradually reduces in diameter from the intake towards the jet nozzle and therefrom increases again. If the shape of the chamber near the jet nozzle differs widely from the rest of the spraying chamber for example, because of projecting parts of a throttle valve, or adaptation of shape of the induction tube to seat the throttle, turbulence takes place, reducing the quantity of mixture passing to the engine, which is an important point at high engine speeds. Generally the shape at this point does not conform to the shape of the rest of the spraying chamber.

Accordingly I overcome this objection by employing in conjunction with a valve of the kind specified a fixed passage inside the valve which conforms with the shape of the rest of the spraying chamber. For instance the surface opposite to the jet nozzle may be integral with a part which carries the jet nozzle or the equivalent.

The accompanying drawings show one method of carrying out this invention, the carburetor in this case being provided with a sliding cylindrical throttle valve. In these,

Figure 1 is a central vertical section through the spraying chamber or induction passage.

Figure 2 is a similar view of part of the carburetor dismantled.

Figure 3 is a plan view of the part shown in Figure 2, and

Figure 4 is an elevation of the throttle valve.

Like figures indicate like parts throughout the drawings.

The invention comprises a casing 10 having a transverse bore 11 and a longitudinal bore 12. A block 13 is disposed in the transverse bore of the casing and has a transverse bore 14 which registers with the longitudinal bore 12 to form an induction passage for supplying combustible mixture to an engine. A thin annular space or slot 15 is left between the block and the casing to receive a tubular throttle valve 16, which may be rotatable but is preferable 75 slidable therein. In the present instance the throttle slides in the slot and is prevented from rotating by a key 17. The valve may be raised by a Bowden wire 18 and seated by a spring 19.

The induction passage formed by the bores 12 and 14 is preferably of Venturi shape and is designed to have a substantially smooth and continuous surface. When the throttle is fully open there are no parts projecting into the passage, and the slot 15 is so narrow that from a practical standpoint the inner surface of the wall is continuous. It will also be noted that the seat of the valve is within the slot and does not affect the shape of the passage. Thus when the throttle is open the induction passage is clear and unobstructed.

The block 13 is provided with a recess 20 which forms a fuel well and a plurality of fuel inlets or nozzles 21 which spray fuel into the induction passage. Fuel is supplied to the well in any suitable manner, such as by a conventional float chamber, through a calibrated plug 22. If desired a fuel chamber 23 may be formed in the upper part of the well by a plug 24 placed between the ends of the recess 20.

Any suitable extra air valve such as 25 may also be used with the device, if desired.

The invention is particularly applicable to racing or high speed engines. With such engines it does not matter if the induction passage of the carburetor is obstructed at lower speeds, but to secure high speed it is essential that the passage be perfectly clear and unobstructed so as to offer the least possible resistance to the passage of mixture and to prevent all eddying and turbulence, which causes a reduction in the quantity of mixture supplied.

It is to be understood that the invention is not limited to the particular details of construction which have been described for the sake of illustration, but includes modifications which come within the scope of the appended claims.

What I claim as my invention and desire to secure by Letters Patent is:—

- 20 1. In a carburetor, in combination, a casing having a bore therein, a block disposed in the casing and having a transverse bore which registers with the bore in the casing to form a substantially continuous induction passage, a fuel inlet in said passage, and a tubular throttle member disposed around the block and adapted to obstruct said passage.
- 25 2. In a carburetor, in combination, a casing having a longitudinal and a transverse bore, a block disposed concentrically

within the transverse bore and having a bore therein which registers with the longitudinal bore to form a substantially continuous induction passage, a fuel inlet in said passage, and a tubular throttle member disposed in the transverse bore and around the block.

3. In a carburetor, in combination, an induction tube a fuel inlet therein, said tube having a substantially smooth and continuous inner surface and having a circular slot intersecting all the elements of said surface, and a tubular throttle member disposed in said slot.

4. In a carburetor, in combination, a casing having a longitudinal bore therein, a block disposed in the casing and having a transverse bore which registers with the longitudinal bore to form a substantially continuous induction passage, a fuel inlet in said block, and a tubular throttle member disposed around the block and in alignment with the fuel inlet.

In testimony whereof I have signed my name to this specification in the presence of two subscribing witnesses.

FREDERICK HENRY DE VEULLE.
